Frank E. Richards,

INVENTOR

P. Hickey

WITNESS:

Victor J. Evans

ATTORNEY

UNITED STATES PATENT OFFICE

FRANK E. RICHARDS, OF JACKSON, MISSISSIPPI

FOLDING PANTS PRESS

Application filed April 1, 1929. Serial No. 351,784.

The object of this, my present invention, is the provision of a pressing device for trousers that shall be of a simple construction but thoroughly efficient in practical use and likewise one that is constructed of sections so that the same is foldable to provide a small package of a size that may be conveniently carried in a suit case when not desired for use.

10 A further object is the provision of a pressing device for this purpose in which the side or presser plates have their inner faces provided with longitudinal grooves to receive therein the seams of the trousers and have 15 their inner faces at one of their ends provided with transverse grooves to receive the cuffs of the trousers therein so that the trousers, at the folds thereof may be effectively pressed without exerting undue pressure 20 upon the seams or upon the cuffs.

To the attainment of the foregoing and other objects which will present themselves as the nature of the invention is better understood, the improvement also consists in 25 certain other novel features of construction, combination and operative association of parts, one satisfactory embodiment of which is disclosed by the accompanying drawings.

30 In the drawings:

Figure 1 is a side elevation of my improvement.

Figure 2 is a sectional view on the line 2—2 of Figure 1.

Figure 3 is a sectional view approximately 35 on the line 3—3 of Figure 1.

Figure 4 is a fragmentary elevation to illustrate the manner in which the pivot pins are coupled, the coupling being in section.

Figure 5 is a fragmentary plan view showing 40 the device in open position.

Obviously my improved pressing device may be constructed of any desired material and as disclosed by the drawings the same 45 comprises side members or plates. Each of the sides includes an upper board or section 1 and a lower board or section 2. The confronting edges of the sections are hingedly connected, as indicated by the character 3 50 whereby these sections may be folded against

each other to provide a small and compact package when the device is not in use.

Each of the sections of one of the side members or plates is centrally formed with a longitudinal groove 4 and the lower edge of the lower section is provided with transverse groove 5. These grooves of course are on the inner face of the side member or plate and are designed to receive therein respectively the side seams of the trousers and the 60 cuffs in the trousers when a pair of trousers is arranged between the plates for pressing. The sections of the other side member are made of relatively thin material.

The side members or plates of the improvement on one of their ends have secured thereto the inner and flattened body portions 6 of lapping eyes 7. The pairs of eye members are suitably spaced away from each other and receive therethrough a pivot rod 8. By reference to the drawings it will be noted 65 that both ends of the pivot rod 8 are headed and also by reference to Figure 4 of the drawings it will be seen that the confronting ends of the said pivot rods are threaded for engagement with similar pitched threads of a turnbuckle or coupling 10. The threads 9 70 may be extended so that the coupling may be screwed off of one rod onto the other or the rod sections may be disassociated by turning one to unscrew the same from engagement with the coupling or turnbuckle 10.

In the showing of the drawings the side members of the improvement are constructed of wood and the same throughout their 75 length are reinforced on their upper faces by transversely arranged metal or wood plates 11, and to these plates all of the eye carrying elements 6, except the upper and lower elements, are connected.

Fixedly secured on the plates 11, on one of the sides of the improvement there are plates or leaves 12 that comprise the fixed 80 elements of clamps. The outer ends of these leaves are rounded and are hingedly connected, as at 13, to the rounded ends of confronting leaf sections 14. The leaves 12 of the 85 clamps have passed therethrough bolt members 15 which are received through somewhat elongated openings in the swingable leaf sec- 90

tions 14, and these bolts are engaged by wing nuts 16. By adjusting the wing nuts when the side members are swung together to press a pair of trousers therebetween, it will be apparent that the pressing operation may be accomplished in an easy and expeditious manner. As stated, when the device is not required for use the sections comprising the same are folded one against the other. The turnbuckle or coupling holds the pivot rod sections 8 in longitudinal alinement and sustains the device in its set up condition.

The simplicity of the construction and the advantages thereof will, it is thought, be understood and appreciated by those skilled in the art to which such invention relates, so that further detailed description is not required. Obviously I do not wish to be restricted to the precise details herein set forth and, therefore, hold myself entitled to make such changes therefrom as fairly fall within the scope of what I claim.

Having described the invention, I claim:

1. A trousers pressing device, comprising two side members, each comprising two sections, each pair of sections being hingedly connected, a pivot rod at one edge of the side members for hingedly connecting the same, and said pivot comprising a pair of members that have their confronting ends provided with different pitched threads, a turn buckle removably connecting the members and adjustable clamping means on the free edge of the side members.

2. A trousers pressing device, comprising two side members, each comprising two sections, and both pair of sections being hingedly connected, a pivot rod at one edge of the side members for hingedly connecting the same, and said pivot comprising a pair of members, and adjustable element removably connecting the confronting ends of the rod members, clamps each comprising a leaf member that is fixed on one of the sides and a hinged leaf connected with the fixed leaf member and which is swingable to contact with the opposite side, bolt members passing through the leaves and wing nuts engaging the bolts.

3. A trousers presser comprising two side members, each comprising two sections, each pair of sections being hingedly connected, transversely arranged reinforcing plates for the sides, outstanding ears arranged inlapping pairs having inner portions fixed to the sides and having their outer eye portions projecting beyond one edge of the sides, a pivot rod having its ends held passed through the eyes, said rod comprising two sections whose ends are arranged in a line with the confronting ends of the sides and the said ends of the pivots being provided with opposite pitched threads, a turn buckle engaging with the threads, clamps on the free edges of the side members, each including a fixed leaf

section and a swingable leaf section and removable and adjusting binding elements for the leaf sections.

In testimony whereof I affix my signature.

FRANK E. RICHARDS.
